US00D484236S

(12) **United States Design Patent** (10) Patent No.: **US D484,236 S**
 Renz et al. (45) Date of Patent: ** Dec. 23, 2003

(54) **BREAST CUP**

(75) Inventors: **Charles John Renz**, Briarcliff Manor, NY (US); **David Robson**, Riverside, RI (US); **Marco Wo**, Providence, RI (US); **Christopher Kampf**, Cranston, RI (US); **Aidan J. Petrie**, Jamestown, RI (US); **Michael C. Pereira**, Smithfield, RI (US)

(73) Assignee: **Playtex Products, Inc.**, Westport, CT (US)

(**) Term: **14 Years**

(21) Appl. No.: **29/168,179**

(22) Filed: **Sep. 27, 2002**

(51) LOC (7) Cl. **24-02**

(52) U.S. Cl. **D24/109**

(58) Field of Search D24/109, 108, D24/129; 604/75, 76, 74, 77
